UNITED STATES PATENT OFFICE.

ARTHUR WICKERSHAM, OF HEREFORD, SOUTH DAKOTA.

CUSPIDOR-LIFTER.

1,260,111.

Specification of Letters Patent. Patented Mar. 19, 1918.

Application filed August 17, 1917. Serial No. 186,755.

To all whom it may concern:

Be it known that I, ARTHUR WICKERSHAM, a citizen of the United States, residing at Hereford, in the county of Meade and State of South Dakota, have invented new and useful Improvements in Cuspidor-Lifters, of which the following is a specification.

This invention is an improved device for lifting and carrying cuspidors and the like, 10 the object of the invention being to provide an improved device of this character which is simple in construction, is strong and durable, is adapted to be easily operated to engage and release a cuspidor and by means 15 of which a cuspidor can be rigidly maintained in an upright position while it is being carried and may be also readily tilted and dumped and the cleaning thereof greatly facilitated.

20 The invention consists in the construction, combination and arrangement of devices hereinafter described and claimed.

In the accompanying drawings:—

Figure 1 is a side elevation of a cuspidor 25 lifter and carrier constructed and arranged in accordance with my invention.

Fig. 2 is an elevation of the same at right-angles to Fig. 1.

Fig. 3 is a sectional view of the same on 30 the plane indicated by the line 3—3 of Fig. 1.

My improved cuspidor lifter and carrier comprises a pair of members 1, 2, each of 35 which constitutes a bar of metal, of suitable dimensions, the said members being crossed and pivotally connected together as at 3. The member 1 has an inwardly curved lower end 4 and is provided at its upper end with an arm 5 which is arranged at an angle 40 thereto and to the upper end of which is attached a handle 6, the handle being formed by bending a strip of suitable metal in substantially elliptical form and by bending the ends of said strip to form lugs 7 which are secured on opposite sides of the 45 upper end of the arm 5 by rivets 8, the handle being arranged at right-angles to the arm. A segmental jaw 9 which is arranged at right-angles to the general plane of the

member 1 is secured at a point near its 50 center to the laterally turned end 10 of the curved portion 4 of said member 1. This jaw is adapted to engage one side of a cuspidor, indicated at *a*, and is provided with a facing 11 of rubber or other suitable 55 material.

The member 2 is identical in construction with the member 1 excepting that its lower portion is bent laterally at a slight angle as at 12. The handle 13 of the member 2 is identical in construction with the handle 6 and is secured on the upper end of the arm 14. On one side of the member 2 is a bar 15 which is secured thereto and is formed with an offset 16 through which the member 1 extends. Said bar has an outwardly bent lower portion 17 which diverges from the corresponding portion 12 of the member 2 and said portions 12, 15, respectively, terminate in inwardly extending 70 curved portions 18, 19, which are connected together by a segmental jaw 20, said jaw being riveted to outwardly turned lugs 21, 22 with which said curved portions 18, 19 are respectively formed. The jaw 20 is provided with a facing 23 of rubber or other suitable material and is arranged to engage the cuspidor on the side opposite the jaw 9. 75

It will be understood that the handles of the implement can be readily grasped and manipulated to cause the jaws of the implement to be gripped on opposite sides of a cuspidor so that the cuspidor can be readily lifted, carried and emptied without having to handle the same and the cleaning of the 85 cuspidor can be also greatly facilitated. The jaws can also be readily disengaged from the cuspidor to release the latter, as will be understood.

Having thus described my invention, I 90 claim:—

An implement of the class described comprising a pair of members arranged in crossed relation, pivotally connected together and provided with handles at their 95 upper ends, the lower ends of said members being curved inwardly, a segmental jaw secured to the curved lower end of one of the

members and arranged to engage one side of a cupidor, a bar on one side of the other member, corresponding in shape therewith, provided with an offset portion through 5 which the first-named member extends, said second-named member and said bar having downwardly diverging lower ends, and a

segmental jaw secured to and connecting said downwardly diverging ends and adapted to engage a cupidor on the side opposite 10 the first-named jaw.

In testimony whereof I affix my signature.

ARTHUR WICKERSHAM.
